UNITED STATES PATENT OFFICE.

FRANK T. HYATT, OF NORWALK, CONNECTICUT.

RELINING RUBBER DENTAL PLATES.

SPECIFICATION forming part of Letters Patent No. 293,739, dated February 19, 1884.

Application filed October 2, 1883. (Model.)

To all whom it may concern:

Be it known that I, FRANK T. HYATT, of Norwalk, in the county of Fairfield and State of Connecticut, have invented a new and Improved Process for Relining Dental Plates, of which the following is a full, clear, and exact description.

It frequently occurs that rubber dental plates do not fit the roof of the mouth after 10 the said plates have been used a number of years, on account of changes that have taken place in the shape of the roof of the mouth, and in such cases a new set of teeth must be made.

15 The object of my invention is to reline the plates or provide the old gums and teeth with a new roof-plate made to fit against the roof of the mouth.

In carrying out my improved process, I cut 20 out the old plate, so that only the gums holding the teeth remain, and then I form a thin lining of rubber on the top of the gums, and by means of this lining I unite the gums and form a new roof-plate.

25 Reference is to be had to the accompanying drawings, forming a part of this specification, in which similar letters of reference indicate corresponding parts in both figures.

Figure 1 is a plan view of the under side of 30 one set of teeth provided with my improvement. Fig. 2 is an enlarged detail cross-sectional elevation of part of the same on the line $x x$, Fig. 1.

The artificial teeth A are held in gums B, 35 which are embedded in a hard-rubber gum-frame, C, which is made integral with the original roof-plate, which original roof-plate I cut out, as shown by the U-shaped line in Fig. 1. Then a series of notches, a, are formed 40 in the remaining portion of the gum-frame C, on the in and out sides. The upper surface of

the gum-frame C is provided with a plastic lining, D, of rubber, which must be as thin as possible, of which rubber a ridge, D', is also built up on the outer edge of the gum-frame, 4 and a roof-plate, D'', is formed, which is shaped to fit closely against the roof of the mouth, and is provided on its upper surface with the usual suction-recess, E. Tenons b are formed out of the soft rubber within the notches a, 5 which tenons serve to hold the ridge D' and roof D'' on the gum-frame C. The lining D unites the ridge D' and the roof D'' and strengthens the dental plate, and at the same time permits of forming the top of the gum-frame in 5 such a manner that it fits well against the natural gums.

By relining dental plates in the manner described, old plates of teeth, to which the wearer has become accustomed, can at any time be 6 adjusted or changed to fit well in the mouth.

I am aware that it is not new to make the roof of alloy gum or to connect it with the teeth by a metallic base; but

What I do claim as new and of my invention 6 is—

The process of relining dental plates, consisting in first cutting away a portion of the roof-plate, and in notching the remaining portion containing the gum and teeth, applying 7 a thin coating of rubber in the grooved upper portion of the gum-frame, and forming the roof-plate and the ridge above the gums, the new ridge and roof-plate being connected by said thin coating and tenoned to enter notches 7 in the original gum-frame, substantially as set forth.

FRANK T. HYATT.
